UNITED STATES PATENT OFFICE.

GEORGE THOMPSON, OF TORONTO, ONTARIO, CANADA.

DESIGN FOR A PHOTOGRAPH OR PICTURE HOLDER.

No. 39,252.

Specification for Design.

Patented April 7, 1908.

Application filed January 2, 1908. Serial No. 409,102. Term of patent 3½ years.

To all whom it may concern:

Be it known that I, GEORGE THOMPSON, a subject of the King of Great Britain, residing in the city of Toronto, in the county of York, in the Province of Ontario, in the Dominion of Canada, have invented a new, original, and ornamental Design for Photograph or Picture Holders, of which the following is a specification, reference being had to the accompanying drawing, forming part thereof.

The figure is a plan view of a photograph or picture holder, showing my new design.

I claim:

The ornamental design for a photograph or picture holder as shown.

GEO. THOMPSON.
